W. P. Preble

UNITED STATES PATENT OFFICE.

ROYAL E. BIBBINS, OF NEW YORK, N. Y.

COMPASS.

1,385,423.

Specification of Letters Patent. Patented July 26, 1921.

Application filed July 31, 1920. Serial No. 400,323.

To all whom it may concern:

Be it known that I, ROYAL E. BIBBINS, a citizen of the United States, and a resident of the city, county, and State of New York, (whose post-office address is 1133 Broadway, New York city,) have invented certain new and useful Improvements in Compasses, of which the following is a specification.

10 The object of my invention is to provide a device which shall serve as a reliable, commercial compass whether on land, or sea, or when carried by an aeroplane or other air vessel, and shall have as few parts as possible, be free from frictional bearings, and shall have no gearing, cogs, or complicated parts of any kind, to get out of order or adjustment.

15 The main underlying feature of my proved compass is that all the movable parts are suspended in air by the action of the air itself;—each suspended part having its special function in controlling the operation of the device, whether in taking up and responding to the constant and uniform rotative motions of the earth or in resisting and making compensation for the sudden irregular motions of the vessel or other conveyance on which the compass is carried 20 from place to place about the earth's surface.

25 My invention consists broadly of a stationary base-cup by and through which the necessary supporting and driving air supply is fed to the movable devices of the compass, an intermediate floating carrier or vessel adapted and shaped to rest in said base-cup when stationary and to float therein when raised by the supporting air, a 30 movable and adjustable cover for said vessel, and a ball adapted to be located inside said vessel when covered and to spin freely and effectively therein when and as acted upon by the air which is fed to said covered 35 vessel by said base cup.

40 It will be understood that in order to bring about the desired compass action of these associated parts, a proper system of inlets and discharge outlets for the compressed air 45 which is used to secure the stability and effective control of the spinning ball as to its compass action, and its necessary precession to the meridian, must be provided. But the details and arrangement of these inlets 50 and outlets are susceptible of great variation, according to the specific needs of the

instrument and they must be capable of very delicate adjustment, to those needs.

55 In the accompanying drawings I have illustrated the simplest and most effective type of compass which I have as yet devised embodying the above invention:—

Figure 1, is a top plan.

Fig. 2, is a front elevation.

Fig. 3, is a vertical section on line A—A of Fig. 1.

Same letters indicate similar parts in the various figures.

A, is the base cup which is adapted and intended to be mounted upon some fixed support so that its motion through space in obedience to the rotation of the earth, will be the same as that of any other so-called fixed object. This base cup is held poised by 70 gimbal rings or other devices capable of adapting themselves to the swaying or swinging motions of the ship or other vessel on which the compass is to be carried and to the constant turning of the earth on its axis, as well as to sudden shocks or jars 75 from whatever cause. As is well known the purpose of thus supporting the base cup is to keep it apparently always level or balanced horizontally, and through this base cup a passage or channel a, is made to permit the passage of air under pressure from 80 a source of supply, not shown, to the hemispherical chamber B, constituting the cup part of said base. It is to be understood that the inner surface of this cup-shaped 85 chamber must be made as smooth, uniform and frictionless as art can make it, so that the air passing therethrough, as hereinafter explained, shall not meet any, even microscopically minute, projections or depressions to deflect its course.

90 C, is the intermediate floating carrier or vessel which as shown is a delicately molded shell, pierced by the air passage c, d, e, and terminating in the nozzle, f, and having both 95 its outer and inner surfaces as smooth and frictionless as skill can make them. This vessel is preferably made of aluminum, and requires great accuracy in its construction. The function of this vessel is to receive and 100 compensate, as it were, the unavoidable tendency of variations in the tip of the base cup and consequently variations in the delivery of the supporting and driving air, to cause corresponding variations in the action of the 105 driven ball D, which, as shown, closely fits in said floating vessel without contact there- 110

with except through the medium of the air itself.

The ball D, when at rest lies gently within the carrier C, which in turn rests in the 5 base cup A. But the ball is set in motion, which afterward becomes as rapid as may be found necessary, by the air stream issuing from the nozzle f, and traveling over the surface of the ball and the concave surface 10 of the floating carrier itself. The inertia excited within the spinning ball D, when at the proper speed secures for the ball a control over the floating carrier and this control enables said carrier to compensate, as before 15 stated, for the variations received by the carrier from the base-cup but, by this means, not permitted to act unfavorably to its compass action, upon the spinning ball D. Obviously the periphery of this ball must be 20 uniformly smooth and great care is needed thereby in its manufacture.

E is the cover of the carrier, provided with an expanded vizor-piece for the escape of the used air F. The cover is adjustably 25 secured to the carrier, preferably, by allowing the cover to press downwardly under gravity upon a threaded ring g, upon said carrier and making this ring adjustable on said carrier to vary in great delicacy the 30 space through which the air is admitted under the cover and over the spinning ball. A threaded ring h, upon the upper edge of the base cup adjustably controls the outlet 35 of the air from the space between the under side of the carrier and the concave surface of the cup-chamber.

As shown the cover E has a broad flange i of an annular character upon which the usual compass card may be placed and secured.

The operation of my improved compass in actual practice is as follows:—

When the compass is set up in a ship's binnacle or otherwise as occasion requires,

the device is so placed that the vizor F is 45 toward the east, and the nozzle f, is so set as to deliver the air toward the west on the under side of the ball D. Under the impetus of the constantly supplied air the ball will spin with proportionate rapidity in the 50 direction of the arrow, that is, from west to east, exactly as the earth spins. The axis of the spinning ball will therefore be directly north and south. By setting the compass card on the cover flange of the cover 55 E, so that the north point corresponds with the extremity of the ball's axis, the north and south line will keep to the meridian as long as the spinning ball continues to revolve upon an unchanged axis, and this axis 60 will not change so long as the speed of rotation of the ball is maintained. The pull of the inertia thus maintained in the ball upon the covered vessel in which it turns will be found at all times sufficient to draw 65 back that vessel and consequently the compass card to the stabilized position whenever any outside shock or cause displaces or tends to displace said vessel from its normal relation to the spinning ball.

I claim:—

A compass which comprises a base cup adapted to permit a supply of air to pass therethrough to the chamber of said cup, a floating vessel adapted and shaped to rest 75 in said base cup when stationary and to float therein when raised by the supporting air, a removable and adjustable cover for said vessel, and a ball adapted to be located inside said vessel when covered and to spin freely 80 and effectively therein when, and as, acted upon by the air fed to said vessel through said base cup.

ROYAL E. BIBBINS.
